The Schedule referred to in these Letters Patent and making part of the same.

To all whom it may concern:

Be it known that we, NICHOLAS S. The distinguishing feature of our said ornamental design consists in the compound ornamentation *a b c d e* upon a panel, *f*, surrounded by a border-moulding, *g*, on one or more of the doors or plates, *H I J*, of a

stove, the same being shaped and arranged together, so as to appear as represented in the aforesaid photograph.

What we claim as our invention or production, and desire to secure by Letters Patent, is—

The design for a plate, or plates of a cooking-stove, as herein shown and described.

In testimony whereof, we hereunto set our hands, this 3d day of June, A. D. 1869.
